COMBINED HAIR BRUSH AND HAIR LIFTER

Anthony Battaglia, 455 NW. 202nd Terrace,
Miami, Fla. 33169

Filed Oct. 17, 1966, Ser. No. 4,303

Term of patent 14 years

(Cl. D9—2)

I claim:

The ornamental design for a combined hair brush and hair lifter, substantially as shown.
